UNITED STATES PATENT OFFICE.

NOBLE T. GREENE, OF PROVIDENCE, RHODE ISLAND.

EXHAUST-VALVE GEAR FOR ENGINES.

SPECIFICATION forming part of Letters Patent No. 425,219, dated April 8, 1890.

Application filed December 10, 1889. Serial No. 333,247. (No model.)

To all whom it may concern:

Be it known that I, NOBLE T. GREENE, a citizen of the United States, residing at Providence, in the county of Providence and State of Rhode Island, have invented certain new and useful Improvements in Exhaust-Valve Gear for Steam-Engines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention has relation to the valve-operating mechanism of automatic cut-off engines having slide-valves; and it consists, essentially, of a steam-engine having the cylinder thereof provided with two suitably-mounted governor-controlled inlet-valves, in combination with two exhaust-valves reciprocating transversely of the cylinder by means of a rocker-shaft actuated by gears vibrating by and in unison with the main eccentric. 20 The object of my invention is to simplify and cheapen the construction of the exhaust-valve mechanism of steam-engines having slide-valves. By means of my improvement the relation of the exhaust-valves to the 25 steam-valves as to opening and closing can be readily changed when desired. I employ but one eccentric to actuate the four slide-valves. The eccentric-rod connects with a loosely-mounted rocker-lever carrying at its 30 upper end a link which is jointed to the sliding bar, the latter carrying spring-tappets adapted to intermittently engage levers that operate the steam-valves. To the lower end of the rocker-lever is secured a bevel-toothed 35 wheel, which meshes into a similar wheel adjustably secured to a horizontal rocker-shaft carrying arms or levers which reciprocate the exhaust-valves transversely of the cylinder, the invention being an improvement on 40 the exhaust mechanism shown and described in United States Patent No. 12,507, granted to me March 13, 1855.

In the accompanying drawings, Figure 1 is a side elevation of a steam-engine in partial section, viewed from the back, as provided with my device for operating the exhaust-

valves. Fig. 2 is a transverse sectional view, taken on line $x-x$ of Fig. 1, through the back exhaust-ports, &c. Fig. 3 is a partial side elevation showing a slight change in the manner of mounting the rocker-shaft and valve-connections, and Fig. 4 is a cross-sectional view taken on line $o-o$ of Fig. 3.

In the drawings, a indicates the steam-cylinder of a steam-engine; b , the bed piece or frame; p , the pillow-block or main bearing; s , the main shaft, and e the eccentric mounted thereon.

i designates the rocker-lever, loosely mounted on the stud k , secured to the frame, as common. A bevel-wheel or miter-gear w is secured to the axis of the lever i and vibrates back and forth in unison with the lever, motion being transmitted to the latter by means of the eccentric-rod e' , jointed thereto. A shaft c , which I term a "rocker-shaft," extends parallel with the cylinder and is supported in bearings t^2 t^3 . The forward end of this shaft is provided with a miter-gear w , adjustably secured thereto by a set-screw s^2 . t^2 This gear intergears with and receives motion from the other gear-wheel w , before described. In this arrangement the exhaust-valves m are provided with a series of short narrow ports and travel crosswise of the cylinder. Each 80 valve-stem extends through the back bonnet or cover d and is secured to a cross-head d' , fitted to travel in guides formed in the cover. An arm or lever l is secured to the shaft c contiguous to each valve, motion being transmitted to the valve by means of a link l^2 , jointed to the cross-head and lever. l^2 85

From the foregoing it is obvious that the angular movement of the rocker-lever will be sufficient to reciprocate the narrow-ported 90 exhaust-valves back and forth past the cylinder-ports o , as in opening and closing.

In the arrangement shown in Figs 3 and 4 the relative position of the levers l to the links l^2 is such that the maximum travel of the 95 valves is attained by a given angular movement of the lever i , whereas in Figs. 1 and 2 the location of the rocker-shaft is such that the angular movement produces a minimum travel of the valves. It is to be understood 100 that the two valves m are arranged or "set" in relation to each other as usual, the corre-

sponding levers l , &c., being adjusted so as to open and close the valves alternately by means of the gear-driven rocker-shaft c .

The steam-valves and mechanism for operating them are well known, and consequently need not be described in detail. I would state, however, that a mounted slide-bar u is made to travel to and fro parallel with the axis of the engine by means of a connecting rod or link e^2 , jointed both to the bar and rocker-lever i . The bar u carries two reversely-arranged tappets u^2 , which in traveling engage hooks or latches f' , mounted at the lower ends of the valve-levers g , which latter are secured to the ends of the valve-stems f , all as common. The steam-valves n travel longitudinally of the cylinder, the reciprocating movement of the bar u producing an engagement of the tappets with the levers g and causes the valves to open, thereby admitting steam alternately to the ends of the cylinder. The valves close after being released by means of weights or vacuum-pots v^2 , jointed to the valve-levers.

25 The relative height or position of the tappets, and consequently the amount of surface in contact with the valve-levers for any stroke, is determined by a lever t^1 , actuated by a governor, all substantially as usual to 30 automatic cut-off steam-engines.

The upper end of the rocker-lever i is provided with a handle i' , by means of which the engineer is enabled to operate all the valves simultaneously after first unhooking the eccentric-rod e' . By also unhooking the slide-bar connection e^2 the exhaust - valves only will be operated upon vibrating the rocker-lever back and forth.

In use steam passes from the steam-chest 40 through the uncovered steam-port into the cylinder. The steam, acting upon the piston, forces the latter ahead and by means of the usual rods, &c., causes the shaft to revolve. At the proper time, as determined by the 45 governor, the tappet is released from the steam-

lever, the weight instantly closing the valve, thus cutting off live steam from the cylinder. The corresponding exhaust-valve is kept closed meanwhile, (the forward one being open.) As the piston reaches the end of its stroke the 50 continued action of the eccentric closes the last - named exhaust - valve and gradually opens the other one. The expanded steam then passes from the cylinder, through the exhaust-ports o and valve, into the exhaust-chest o^2 , and finally enters the escape-pipe o^3 .

Obviously the ratio of the gears w may be changed without departing from the spirit of the invention—that is to say, the gear mounted on the axis of the rocker-lever i may be 60 somewhat larger than the fellow gear secured to the shaft c . This arrangement would give to the valve-operating shaft c a greater angular movement, thereby opening the exhaust-valves quicker and permitting of an increased 65 lap, if desired.

I do not claim, broadly, as my invention a steam-engine having its four valves actuated by a single eccentric; but

What I do claim is—

In an automatic cut-off steam-engine, the combination, with governor-controlled steam-valves moving longitudinally of the steam-cylinder, of two exhaust-valves reciprocating transversely of the cylinder by mechanism 75 consisting of an eccentric-driven rocker-lever, a pair of bevel-gears actuated by and in unison with said rocker-lever, a mounted rocker-shaft having one of the bevel-gears secured thereto, levers or arms adjustably secured to 80 the shaft, and links or other analogous connections jointed to the levers and connected with the exhaust-valves, substantially as hereinbefore described.

In testimony whereof I have affixed my signature in presence of two witnesses.

NOBLE T. GREENE.
